JAMES W. MALOY, OF BOSTON, MASSACHUSETTS.

Letters Patent No. 71,773, dated December 3, 1867.

IMPROVEMENT IN PRESSURE-GAUGES.

The Schedule referred to in these Letters Patent and making part of the same.

Be it known that I, JAMES W. MALOY, of Boston, in the county of Suffolk, and State of Massachusetts, have invented a new and improved Pressure-Gauge, of which the following is a full, clear, and exact description, reference being had to the accompanying drawings, making a part of this specification, in which—

Figure 1 represents an elevation of a portion of a fire-extinguisher to which my invention is applied.

Figure 2 is a view of the interior mechanism of the gauge, and also a portion of the top, in perspective.

Figure 3 is a top view of a fire-extinguisher, and

Figure 4 represents the adjustable spring.

The nature of my invention consists in an arrangement and combination of mechanism through which a flexible metallic diaphragm is made to act upon an index, to show upon the dial the pressure of steam, gas, or other fluid.

The invention also consists in so constructing and arranging the parts as to enable them to be easily removed altogether for repairs or adjustment, and as readily replaced, without the necessity of removing the casing which contains them.

My invention is particularly adapted to be applied to the so-called fire-extinguishers which are charged with a certain kind of gas to be used for extinguishing fires. In these extinguishers the gases with which they are charged are highly compressed, and the apparatus is laid away, all ready for use when occasion requires. When thus disposed of for any considerable length of time, the gas is liable to escape, and the extinguisher is rendered useless in any emergency.

By means of a gauge, as hereinafter described, the exact condition of the gas in the extinguisher may always be determined, so that, in the event of a deficiency at any time, the apparatus may be recharged and its efficiency be always insured. The device may also be applied to steam-boilers, &c., for indicating the pressure of steam.

Referring to the drawings, *a* represents the casing of a fire-extinguisher, which is of cylindrical form, of any suitable length or diameter, and having two openings, *a' a''*, in the top, for the insertion respectively of the discharge-pipe of the gases and the gauge. These openings are surrounded by a frame, *c c'*, of different diameters, and connected together so as to be firmly set in the casing. Fig. 2 represents the gauge on an enlarged scale, and it consists in a metallic casing, *b*, the bottom of which is composed of a thin, flexible metallic diaphragm, *d*, which is curved outwardly, so that any pressure upon its outer surface will force it inwards, more or less, according to the degree of pressure exerted. On the inner surface of the diaphragm *d* rests a button or circular plate, *e*, having a stem, *e'*, projecting upwards and passing loosely through an opening in the base or support of a standard, *g*, which latter extends upwards in the casing *b*, being maintained in position by means of the cross-bars *h h* and *m* extending across the inside of the case. The stem *e'* of the button *e* supports or presses against the short arm *i* of a bent lever, *i k*, which is fulcrumed in the base or support *f* at one side of the latter. The long arm of the lever *k* extends upwards, and to its upper end is attached, at right angles, a rack, *l*, fitted to slide freely in a groove in a cross-piece, *m*, attached to the standard *g*. To the lower part of the rear of the lever *k* is attached a spring, *k'*, which extends upwards, and at its free end bears against the inner surface of the casing *b*, and serves to press the lever *k* inwards. The spring *k'* is provided with a slot, so that it can be fixed higher or lower upon the lever *k*, in order to adjust it to the pressure required. The rack *l* engages in a pinion, *n*, journalled in bearings projecting from the standard *g*, as shown. The shaft of the pinion *n* projects upwards and forms an arbor, on which is fixed a pointer, *o*, that turns with the pinion. The dial *p* is made of paper, properly marked, and attached to a plate which rests upon a threaded ring, *s*, which latter also serves to hold in place the grooved cross-piece *m*. The dial is covered by a sheet of mica, *r*, secured in place by the ring *t* which surmounts the casing *b*.

The parts, being all put together, may be readily inserted in the casing *b*, and are secured by the rings *s* and *t* in the same. The casing *b* is screwed or otherwise secured in the opening *a'* of the extinguisher *a*, the dial being flush or nearly so with the top or surface of the same, so that the apparatus can be moved about or transported without endangering the gauge. When inserted in its place in the extinguisher, the latter may be charged with the required quantity of gas, the pressure of the same actuating the indicator through the metallic

diaphragm and connecting mechanism, and thus determining the amount of gas contained in the extinguisher. Should the gas escape from the extinguisher, the state of the same can always be determined by a glance at the indicator, and the proper steps be immediately taken to remedy the defect, by refilling the extinguisher.

The parts are very simple in their construction, easily adjusted, and can be readily taken out for repairs, should occasion require, without the necessity of removing the casing *b* from the extinguisher, or from a boiler, or other apparatus to which it may be attached.

What I claim as my invention, and desire to secure by Letters Patent, is—

1. The combination with a flexible diaphragm of the button *e*, and stem *e'*, the lever *i k*, and spring *k'*, as specified.

2. I claim the combination of a single lever, *i k*, rack *l*, sliding cross-piece *m* attached to the standard *g*, and pinion *n*, as and for the purpose set forth.

3. I claim the standard *g*, and the support *f* and cross-pieces *h*, in connection with the operative parts of the gauge, so constructed and arranged as to enable them to be easily removed from the casing *b*, by simply unscrewing the ring *s*, substantially as set forth.

4. I claim the attachment of a gauge to the top plate of a fire-extinguisher, substantially as specified. In testimony whereof, I have signed my name to this specification in the presence of two subscribing witnesses.

JAMES W. MALOY.
